HUMIDIFYING SYSTEM

Robert H. Worrall, Washington, D. C.

Application September 8, 1933, Serial No. 688,609

4 Claims. (Cl. 261—103)

(Granted under the act of March 3, 1883, as
amended April 30, 1928; 370 O. G. 757)

This invention relates to a humidifying system and has for an object to provide an improved humidifier especially adapted for use in combination with any of several types of conventional heating mechanisms.

Another object is to provide a humidifying system that may be used in combination with heating systems of various types whether the heating system be electrical, steam, vapor, hot water, hot air, or otherwise.

A further object is to provide a humidifying system which, when once properly adjusted, will operate automatically, without further attention, to supply the necessary amount of humidity.

15 A still further object is to provide a humidifying system which, when the heating system is one dependent on steam, vapor or hot water may make use of the heating medium to supply the moisture for the humidifying system and which 20 may be provided with a separate source of moisture when desired, irrespective of the type of heating medium with which it is to be used.

With the above and other objects in view, this 25 invention consists in the construction, combination and arrangement of parts as will be described more fully hereinafter.

In the drawing:

Fig. 1 shows an elevational, partly broken away view of one form of heating cabinet to which this 30 system has been applied;

Fig. 2 is a section on line 2—2 of Fig. 1;

Fig. 3 is a partly broken away elevational view of a modified form wherein the humidifying system uses an independent source of moisture.

35 There is shown at 10 a heating cabinet including a heating unit at 11. The front of this cabinet 10 is closed with a slidable door 12 having a series of louvres 13 through which the heated air may leave the cabinet. The cold air enters cabinet 10 at the bottom 14 which is spaced away from the floor or other supporting surface, passes about heating unit 11, about the humidifying system 15 constituting this invention, and out through the louvres 13, the door 12 being 40 slidably removable when necessary to gain access to either the heating unit 11 or the humidifying system 15. The heating unit 11 is illustrated as an example of any type of suitable heating unit that may be used. As here shown, heating unit 50 11 consists of one or more copper tubes 16 to which are attached a plurality of aluminum or copper fins 17. The copper tubes 16 may be heated by any suitable heating medium such as hot water, vapor or steam entering therein from a T-joint 18 connecting to a heating medium

supply pipe 19 through a conventional, thermostatically controlled valve 20. A return pipe 21 is provided at the other end of tubes 16 for returning the cooled heating medium to the source of heat. An extra pipe 22 connected to T-joint 5 18 leads through a thermostat 23 and past a needle valve 24 on a pipe 33 on which is supported a perforated tube 25 which tube is enclosed in a tubular wick 26. Another and much larger wick 27 depends from perforated tube 25, 10 its depending lower end being held taut by a spring rod 28 supported at 29. Spring rod 28 also serves to support a drip pan 30 by means of a sling 31 secured on spring rod 28 and a pin 32 passed through the sides of the trough 30 and 15 over one end of the spring rod 28.

In Fig. 3 a pipe 40 supplies water from an independent source of supply past the thermostat valve 23 to pipe 33 so that it is not necessary to rely on the heating unit 41 to supply the moisture. In this case the heating unit 41 may be heated by heating medium other than steam, hot water or vapor. Thus electrical heating coils may be contained within the pipes 42 to heat the fins 43. Alternatively, the pipes 42 may have 25 any other heating medium passed therethrough such as hot combustion gases or the like.

In operation, the heating medium enters the heating unit from the source of supply and serves to heat the fins placed thereon. These fins in 30 turn heat the air entering the heating cabinet 10 from the bottom 14, thermostat valve 20 controlling the supply of the heating medium in the conventional manner. When the air rising from the heating unit is heated to the desired temperature, say, 150°, the thermostat valve 23 opens to allow the moisture to enter the pipe 33, the needle valve 24 being set to control the amount of moisture that will be permitted to reach the 35 perforated tube 25. The moisture then escapes 40 through the perforated tube 25 to wick 26 and drains down over wick 27. The heated air rising from the heating unit passes over the sides of wick 27 with the least amount of resistance, absorbing the moisture therein and carrying it out 45 through the louvres 13. The trough 30 is put in position when the system is initially turned on so as to catch any excess moisture from wick 27 until the needle valve 24 has been properly adjusted so as to keep the amount of moisture passing over wick 27 in balance with the amount that can be taken up by the heated air rising from the heating unit. When this proper balance has been 50 reached the door 12 is opened permitting access to the trough 30 which is removed by merely pull- 55

ing out the pin 32 and pushing aside the sling 31, the door 12 then placed back in operative position. If a lesser degree of humidity is desired the needle valve 24 will be adjusted to supply a smaller amount of moisture to the wick 27. Removal of the trough 30 permits full contact between the rising air and the wick 27, wick 27 being held in the proper position by the spring rod 28.

It will be understood that the above description and accompanying drawing comprehends only the general and preferred embodiment of my invention, and that various changes may be made therein within the scope of the appended claims without sacrificing any of the advantages of this invention.

The herein described invention may be manufactured and used by or for the Government of the United States for governmental purposes without the payment of any royalties thereon.

20 I claim:

1. In combination with a heating unit, a humidifying device, said device comprising a source of moisture, means conducting moisture from said source above the heating unit, and means forming said moisture into a film and exposing said film to the air over said heating medium and below said moisture source, said conducting means comprising a perforated tube, a sleeve wick snugly encircling said perforated tube, said film forming means comprising a second wick tautly contacting with and depending from said sleeve wick.

2. In combination with a heating unit, a humidifying device, said device comprising a source of moisture, means conducting moisture from said source above the heating unit, means forming said moisture into a film and exposing said film to the air over said heating medium and below said moisture source, said conducting means comprising a perforated tube and a wick snugly

fitted on said perforated tube, said film forming means comprising a second wick depending from said first wick, and a spring rod keeping said second wick taut and means supporting said spring rod.

3. In combination with a heating unit, a humidifying device, said device comprising a source of moisture, means conducting moisture from said source above the heating unit, means forming said moisture into a film and exposing said film to the air over said heating medium and below said moisture source, said conducting means comprising a perforated tube and a wick snugly fitted on said perforated tube, said film forming means comprising a second wick depending from said first wick, a spring rod keeping said second wick taut, means supporting said spring rod, a trough, and means for detachably supporting said trough below said wick.

4. In combination with a heating unit, a humidifying device, said device comprising a source of moisture, means conducting moisture from said source above the heating unit, means forming said moisture into a film and exposing said film to the air over said heating medium and below said moisture source, said conducting means comprising a perforated tube and a wick snugly fitted on said perforated tube, said film forming means comprising a second wick depending from said first wick, a spring rod keeping said second wick taut, means supporting said spring rod, a trough, and means for detachably supporting said trough below said wick, said trough supporting means comprising a sling on said spring rod adapted to support one end of said trough and a pin extending through the other end of said trough and of said spring rod.

ROBERT H. WORRALL.
